UNITED STATES PATENT OFFICE.

ROBERT J. HEWETT, OF WESTFIELD, NEW JERSEY.

DIRECTIONALLY-CONTROLLED BLOCK-SIGNAL SYSTEM.

Application filed May 28, 1921. Serial No. 473,267.

To all whom it may concern:

Be it known that I, ROBERT J. HEWETT, a citizen of the United States, residing at Westfield, in the county of Union and State 5 of New Jersey, have invented certain new and useful Improvements in Directionally-Controlled Block-Signal Systems, of which the following is a full, clear, and exact description.

10 My invention relates to directionally controlled block signal systems and particularly to systems such as disclosed in my prior Patent Number 1,362,994, dated December 21, 1920. In that patent I disclosed a system having overlapping line circuits operative to set all the signals in one direction to stop for absolute control of traffic in that direction when a train enters the stretch of track in the opposite direction, and stick 15 relays to break this overlap and render the circuits operative for permissive control of traffic in that direction as a train proceeds in the permitted direction. The stick relay in that system is normally energized and is 20 deenergized by closing a shunt circuit controlled by the track relay and the signal for the particular block, such deenergization resulting in the closing of an auxiliary circuit which is effective to incapacitate the overlap 25 control. The restoring circuit for the stick relay is controlled by the line relay and signal conjointly, being closed when the line relay is energized and before the signal moves from its stop position.

30 One of the objects of this invention is to simplify the circuit arrangement for the stick circuit in such a system. Another object is to increase the factor of safety in the operation of such a system. Still other 35 objects and advantages of my invention will appear from the following description.

My invention contemplates arranging the stick or holding circuit of the overlap control relay under the joint control of the 40 track relay and of the signal in such a way that the track relay must be shunted while the signal is between its clear and stop indication, in order to interrupt the stick circuit and thus break the overlap control. In 45 this way the overlap control of the line circuits is broken only by a train moving in the direction controlled by the signals, while the stick relays retain the overlap control for absolute setting of those signals by a 50 train moving in the opposite direction.

55 Other features of my invention will be

more particularly referred to in the description of the embodiment illustrated in the drawings.

Figs. 1 and 2 are diagrams of a circuit 60 arrangement illustrating my invention and are to be taken together, the latter being a continuation on the right of the former.

The stretch of single track between the two sidings W and X shown in the drawings is divided into block sections T^{10} , T^{11} , T^{12} , T^{13} , T^{14} , T^{15} and T^{16} , and traffic through this stretch is controlled by east bound signals 10, 12, 14 and 16 and by west bound signals 9, 11, 13 and 15. Each track section 65 is provided with a track relay designated by the letter R followed by the number of the block section. Each signal is controlled by a polarized line relay designated by the letter L followed by the number of the signal. 70 The signals are shown as three position signals, and the circuits controlling them are of the usual type for governing three position semaphore signals. In other words, the line circuit for a given line relay 75 is connected to a pole changer operated by the next signal in advance. This line circuit also includes a contact closer under the control of the line relay for the signal next in advance. This is the overlap control, it 80 being apparent that when the line relay in advance is deenergized it will, by dropping the contact closer, break the line circuit for the signal in rear. In this way the deenergizing of a line relay at one end of the 85 block will cause all the line relays for the signals in the direction opposite to that in which the train enters, to be deenergized, and the signals controlling traffic in the opposite direction are thereby all set to stop 90 position for the absolute control of traffic in the direction opposite to that in which the controlling train entered the stretch of track.

In order that these line circuits may operate to control traffic passing through the stretch of track in the direction governed by the signals controlled by these line circuits, a stick relay is provided for each signal, which is designated by the letter S followed by the number of the signal, and this stick relay is normally energized and operates when deenergized to close an auxiliary or branch circuit around the circuit closer controlled by the line relay, or in other 105 words, to break the overlap control.

The line circuit arrangement is similar to

that illustrated in my Patent #1,362,994 above mentioned. Referring to line relay L^{10} , for instance, the circuit may be traced as follows: relay L^{10} , wire 20, circuit controller 21 of track relay R^{10} , wire 22, circuit controller 23 of west bound stick relay S^{11} , wire 24, circuit controller 25 of track relay R^{11} , wire 26 to circuit controller 27 of stick relay S^{12} , wire 28, circuit controller 29 of line relay L^{12} , wires 30 and 31, positive pole changer P, wires 32, 33 and 34, battery B^{12} , wires 35 and 36 and negative pole changer N to the common wire indicated throughout the drawings by the heavy line back to relay L^{10} . Thus it is seen that the line circuit is controlled by the track relays for track sections T^{10} and T^{11} , and by the stick relay for west bound signal 11, and also by the line relay for the signal 12 so long as the stick relay S^{12} is energized and the circuit closer 27 is against its front stop. If the stick relay S^{12} be deenergized, the circuit closer 27 engages the back contact 37, and this line circuit then proceeds from the contact closer 27 to the wire 38 and thence to the wire 31, the circuit closer 29 being eliminated from the circuit. The line circuit for relay L^{12} may be traced in precisely the same way, being controlled by track relays R^{12} and R^{13} and by stick relay S^{13} , and also by line relay L^{14} if stick relay S^{14} be energized. Similarly it will be seen that the circuit for line relay L^{14} is controlled by track relays R^{14} and R^{15} and by stick relay S^{15} , but since signal 14 is the last absolute signal at that end of the stretch of track, the line circuit for track relay L^{14} is not controlled by line relay L^{16} , but by track relay R^{15} only through contact 25, passing thence directly to the pole changer of signal 16.

It will now be seen that if a west bound train enters track section T^{15} , track relay R^{15} drops its circuit closer 25 which breaks the line circuit for relay L^{14} . That relay then drops the circuit closer 29 of the overlap control and thus breaks the line circuit for line relay L^{12} , which in turn drops its circuit closer 29 and breaks the line circuit for relay L^{10} . All of the signals governing east bound traffic are thereby put to stop.

The line circuits for the line relays L^9 , L^{11} , L^{13} and L^{15} for west bound signals 9, 11, 13 and 15 may be traced in a similar manner from which it will be seen that the entrance of an east bound train upon track section T^{10} will set all of the west bound signals to stop.

The signal motor circuits are controlled by circuit closers 81 and 87 of the respective line relays, the former being a neutral contact closer while the latter is polarized. In other words the contact closer 81 is closed both for a normal and reverse polarity of the current of the line relay, and the contact closer 87 is closed by a normal polarity and

opened by a reverse polarity of the current. This operation will be further described in connection with the operation of the stick relays.

Referring for example to east bound stick relay S^{10} at signal 10, the control circuit for this stick relay is as follows: From battery B^{10} positive wire 32, wire 40, stick relay S^{10} , wire 42, contact 43, wire 44, wire 45, contact 46 of circuit controller C^{10} which is operated by signal 10 and normally closed when signal 10 is in its clear position, wire 44 and negative wire 34, 33 to battery B^{10} . In multiple with contact 46 of circuit controller C^{10} , is another circuit controlled by contact 50 of track relay R^{10} as follows: From wire 44, wire 49, contact 50, wire 51 to negative wire 33. Since contacts 46 and 50 are in multiple, both must be opened in order to deenergize stick relay S^{10} . After being deenergized stick relay S^{10} will open its stick circuit contact 43 and this will prevent it from being again energized except by the restoring circuit which is as follows: From battery B^{10} , positive wire 32, wire 40, stick relay S^{10} , wire 52, contact 53 of line relay L^{10} , restoring wire 54, restoring segment 55 of circuit controller C^{10} as it passes over segment 55, wire 85, negative wires 34, 33 to battery B^{10} . East bound stick relay S^{10} , can be deenergized by an east bound train movement only, and not by a west bound train movement. For this reason circuit controller C^{10} is provided also with a contact 48 for the stop position of the signal 10, and contacts 46 and 48 are connected by wire 47. When signal 10 is put to its stop position by the entrance of a west bound train into the track section, the stick circuit of stick relay S^{10} will be held closed through the engagement of the circuit controller C^{10} with contact 48 even when the west bound train enters track section T^{10} and deenergizes track relay R^{10} and thus breaks contact 50. In order to break the stick circuit of stick relay S^{10} , the contact 50 must be broken while the circuit closer C^{10} is out of engagement with both contacts 46 and 48. This can only be effected by the entrance of an east bound train into track section T^{10} .

The complete operation of the system for an east bound train movement may now be explained as follows: The entry of the east bound train into track section T^{10} will deenergize track relay R^{10} which by opening its contact 21 will deenergize line relay L^{10} and this by opening its contact 81 will cause signal 10 to move towards its stop position which causes its circuit controller C^{10} to open its contact 46, and contact 50 of track relay R^{10} being also open east bound stick relay S^{10} will be deenergized and this by opening its front contact 25 cuts off contact 27 of track relay R^{10} , which is the overlap control for station signal 8, not shown, and

by closing its back contact 37 connects the control circuit for signal 8 direct to the pole changer PN which now being reversed—signal 10 being at stop, will cause signal 8 5 to give the 45° indication. As signal 10 moves downward its circuit controller C¹⁰ will make an intermittent or passing contact with restoring segment 55, this however is not now effective since stick relay S¹⁰ was 10 deenergized as soon as circuit controller C¹⁰ opened its contact 46, and since contact 53 is now open. When signal 10 is in its stop position and its circuit controller C¹⁰ closes its contact 48 the circuit for stick relay S¹⁰ 15 is still held open since its stick circuit contact 43 was opened as soon as circuit controller C¹⁰ opened its contact 46.

The entry of the east bound train into track section T¹⁰ having deenergized track 20 relay R¹⁰ it will open its contact 65 and put west bound signal 11 to stop and its circuit controller C¹¹ will then close its contact 48 which will hold west bound stick relay S¹¹ energized while the east bound train is passing 25 through track sections T¹⁰ and T¹¹. This holding circuit is now as follows: From battery B¹¹, positive wire 74, wire 40, stick relay S¹¹ wire 42, contact 43, wire 44, wire 45, wire 47, contact 48 of circuit controller C¹¹, 30 wire 85, negative wire 76, 75 to battery B¹¹. West bound stick relay S¹¹ is thereby held normally energized by the stop position of circuit controller C¹¹ while the east bound train is passing through track sections T¹⁰ 35 and T¹¹.

The movement of the east bound train through the block, track sections T¹⁰ and T¹¹, will therefore deenergize east bound stick relay S¹⁰ but will hold west bound 40 stick relay S¹¹ in its normally energized condition.

When the east bound train clears out of track section T¹¹ track relay R¹¹ will be energized and this by closing its contact 61 45 will energize line relay L¹¹ and this by closing its contact 81 in the motor circuit will clear west bound signal 11 and put circuit controller C¹¹ normal which will open contact 48 and close contact 46. During the 50 movement of circuit controller C¹¹ from contact 48 to contact 46 it will be seen that this part of the holding circuit will be open; the closed condition of contact 50 of track relay R¹¹ will, however, hold the holding circuit 55 closed and hold west bound stick relay S¹¹ energized during this interval.

The closed condition of contact 25 of track relay R¹¹ will close the control circuit for east bound signal 10 and its line relay L¹⁰ 60 will be energized and by closing contact 81 will clear signal 10 to its 45° position. The train being now in track section T¹² signal 12 will be at stop and its pole changer PN being reversed will cause battery B¹² to deliver a negative current to line relay L¹⁰ 65

which throws its polar contact 87 to the open position.

The movement of signal 10 from its stop to its 45° position will cause its circuit controller C¹⁰ to make a passing contact with 70 restoring segment 55 and during this contact the restoring circuit for stick relay S¹⁰ will be closed as follows: From battery B¹⁰, positive wire 32, wire 40, stick relay S¹⁰, wire 52, contact 53 of line relay L¹⁰, wire 54, 75 segment 55 of circuit controller C¹⁰, wire 85, and negative wires 34, 33 to battery B¹⁰. Restoring segment 55 should be of sufficient length to enable stick relay S¹⁰ to be safely energized. After being restored to its normal energized condition stick relay S¹⁰ will be held energized by its stick circuit including contact 43 as has been explained.

The absolute or through control of the west bound signals is effected by the repeating arrangement of the line controlled relays and circuits above described. When an east bound train enters track section T¹⁰, track relay R¹⁰, by opening its contact 65 opens the line control circuit, for west bound line relay L¹¹ at signal 11 which will be deenergized and this by opening its contact 69 will open the next west bound line control circuit for west bound line relay L¹³ at signal 13 which will be deenergized and by opening 90 its contact 69 will open the next west bound line control circuit for west bound line relay L¹⁵ at west bound absolute signal 15. All west bound signals 11, 13 and 15 are thereby put to stop and this sets the block against 95 west bound train movements.

As the east bound train moves along through the block it will deenergize each east bound stick relay in rotation which prevents the east bound absolute control from 100 being effective in the rear of the east bound and provides for the permissive movement of a following east bound train as has been explained. As the east bound train clears away from each west bound signal that 105 signal will be cleared to its 90° position as has been shown for west bound signal 11.

In describing the operation of east bound stick relay S¹⁰ at absolute signal 10 it has been shown that the purpose of said stick 110 relay S¹⁰ and its front contact 25 and back contact 37 is to cut off the overlap control for east bound station signal 8 which signal corresponds to east bound station signal 16 at passing siding X. This arrangement of the stick relay applies only at an absolute signal as shown. At all other intermediate signals as 12 and 14 the east bound stick relays S¹² and S¹⁴ are arranged as follows: taking stick relay S¹² to illustrate:

When the east bound train enters track section T¹² at signal 12 stick relay S¹² will be deenergized in the same way as at absolute signal 10. Its front contact 27 will cut 130

off the east bound absolute control contact 29 of east bound line relay L^{12} and its back contact 37 will connect the line control circuit for absolute signal 10 direct to the pole changer PN of east bound signal 12. The circuit will be as follows: From line control relay L^{10} , wire 20, contact 21 of track relay R^{10} , line wire 22, contact 23, of west bound stick relay S^{11} , wire 24, contact 25 of track relay R^{11} , wire 26, back contact 37 of east bound stick relay S^{12} and wire 38 direct to pole changer PN of east bound signal 12. The presence of the east bound train in track section T^{12} causes east bound signal 12 to be in its stop position and its pole changer PN will thereby be reversed which will deliver negative current from battery B^{12} to east bound line relay L^{10} at absolute signal 10 and this will reverse the polarity of line relay L^{10} and throw its polar contact 87 to its open position which will permit signal 10 to display the 45° indication only.

When the east bound train clears out of track section T^{13} at west bound signal 13, east bound line relay L^{12} will be reversely energized, closing contact 81 and opening contact 87, signal 12 will move to caution or 45° position, and stick relay S^{12} will be returned to its normal condition, while pole changer PN of signal 12 will deliver a current of normal or positive polarity to line relay L^{10} at signal 10 and this will cause its polar contact 87 to be thrown to its closed position which will clear signal 10 to its 90° position.

When the east bound train enters track section T^{14} at signal 14 which is the last signal in the directionally controlled stretch of road the operation of east bound stick relay S^{12} will be the same as stick relay S^{12} .

It will be noted, as above pointed out, that at each east bound stick relay, S^{10} , S^{12} , and S^{14} the second contact 63 controls the line control circuit for the opposite or west bound signal. That is stick relay S^{10} by its contact 63 controls west bound control circuit for signal 11; stick relay S^{12} by its contact 63 controls west bound control circuit for signal 13 and stick relay S^{14} by its contact 63 controls west bound control circuit for signal 15. This is a standard requirement in the design of signal circuits and insures the safe operation of the circuits. If a stick relay should fail to be restored to its normal condition its contact 63 will hold open the opposite control circuit and hold the opposite signals at stop.

For a west bound train movement the circuits and signals and their operation are the same but progressive west bound in successive order from west bound absolute signal 15 at passing siding X to west bound station signal 9 at passing siding W.

It is obvious that various modifications

may be made in the construction and circuit arrangement shown in the drawings and above particularly described within the principle and scope of my invention.

I claim:

1. In a directionally controlled block signal system, a stretch of single track divided into block sections, a track relay for each block section, a plurality of signals along the trackway for controlling traffic in one direction and including one at each end and an intermediate signal, a line relay in control of each signal, normally overlapping line circuits in control of the line relays for absolute control of the signals by a train entering the stretch of track in the opposite direction, and a stick relay operative when the train enters the intermediate block in the direction controlled by the signals to incapacitate the control of the line circuit for the signal to the rear by the line circuit of the intermediate signal, the stick circuit of said stick relay including contacts controlled in parallel by the track relay and signal of the intermediate block, respectively. 70

2. In a directionally controlled block signal system, a stretch of single track divided into block sections, a track relay for each block section, a plurality of signals along the trackway for controlling traffic in one direction and including one at each end and an intermediate signal, a line relay in control of each signal, normally overlapping line circuits in control of the line relays for absolute control of the signals by a train entering the stretch of track in the opposite direction, and a normally energized stick relay operative when deenergized to incapacitate the control of the line circuit for the signal to the rear by the line circuit of the intermediate signal, the stick circuit of said stick relay including contacts controlled in parallel by the track relay and signal of the intermediate block, respectively. 90

3. In a directionally controlled block signal system, a stretch of single track divided into block sections, a track relay for each block section, a plurality of signals along the trackway for controlling traffic in one direction and including one at each end and an intermediate signal, a line relay in control of each signal, normally overlapping line circuits in control of the line relays for absolute control of the signals by a train entering the stretch of track in the opposite direction, a normally energized relay operative when deenergized to incapacitate the control of the line circuit for the signal to the rear by the line circuit of the intermediate signal, means controlled by the track relay of the intermediate block for deenergizing the normally energized relay, and means controlled by the intermediate signal for preventing the deenergizing action of the said track relay when the inter- 110

mediate signal is in either the clear or stop position.

4. In a directionally controlled block signal system, a stretch of single track divided into block sections, a track relay for each block section, a plurality of signals along the trackway for controlling traffic in one direction and including one at each end and an intermediate signal, a line relay in control of each signal, normally overlapping line circuits in control of the line relays for absolute control of the signals by a train entering the stretch of track in the opposite direction, a normally energized relay operative when deenergized to incapacitate the control of the line circuit for the signal to the rear by the line circuit of the intermediate signal, means controlled by the co-action of the track relay of the intermediate block and of the intermediate signal to de-energize the normally energized relay when the track relay is deenergized and the signal is intermediate of its clear and stop positions and means controlled by the line relay 25 of said signal for reenergizing said normally energized relay when the said signal is in said intermediate position.

5. In a directionally controlled block signal system, a stretch of single track divided into block sections, a track relay for each block section, a plurality of signals along the trackway for controlling traffic in one direction and including one at each end and an intermediate signal, a line relay in control of each signal, normally overlapping line circuits in control of the line relays for absolute control of the signals by a train entering the stretch of track in the opposite direction, a normally energized stick relay operative when deenergized to incapacitate the control of the line circuit for the signal to the rear by the line circuit of the intermediate signal, said stick relay having its stick circuit controlled in parallel by the track relay and signal of the intermediate block, and means controlled by the line relay of the intermediate signal and by the intermediate signal operative to restore the stick relay when the said signal is intermediate its clear and stop positions.

6. In a directionally controlled block signal system, a stretch of single track divided into block sections, a track relay for each block section, a plurality of signals along the track way, a line relay in control of each signal, normally closed overlapping line circuits controlling said line relays, a normally energized stick relay operative when deenergized to incapacitate the control by one line circuit of the line circuit in the rear, a circuit closer for the stick circuit of said relay controlled by the track relay of the said advance block and operative to be closed when the block is unoccupied, and a second circuit closer for the

stick circuit in multiple with the first circuit closer and operated by the signal for said advance block to be closed when the signal is in either its clear or stop positions and to be open when the signal is in an intermediate position.

7. In a directionally controlled block signal system, a stretch of single track divided with block sections, a track relay for each block section, a plurality of signals along the track way, a line relay in control of each signal, normally closed overlapping line circuits controlling said line relays, a normally energized stick relay operative when deenergized to incapacitate the control by one line circuit of the line circuit in the rear, and a circuit closer for the stick circuit of said relay operated by the signal for the advance block to be closed when the signal is either in its clear or stop positions.

8. In a directionally controlled block signal system, a stretch of single track divided with block sections, a track relay for each block section, a plurality of signals along the track way, a line relay in control of each signal, normally closed overlapping line circuits controlling said line relays, a normally energized stick relay operative when deenergized to incapacitate the control by one line circuit of the line circuit in the rear, a circuit closer for the stick circuit of said relay controlled by the track relay of the said advance block and operative to be closed when the block is unoccupied, a second circuit closer for the stick circuit in multiple with the first circuit closer and operated by the signal for said advance block to be closed when the signal is in either its clear or stop positions and to be opened when the signal is in an intermediate position, and a restoring circuit for said stick relay operative to reenergize the relay when the said signal is in an intermediate position and the said advance block is unoccupied.

9. In a directionally controlled block signal system, a stretch of single track divided with block sections, a track relay for each block section, a plurality of signals along the track way, a line relay in control of each signal, normally closed overlapping line circuits controlling said line relays, a normally energized stick relay operative when deenergized to incapacitate the control by one line circuit of the line circuit in the rear, a circuit closer for the stick circuit of said relay operated by the signal for the advance block to be closed when the signal is either in its clear or stop positions, and a restoring circuit for said stick relay operative to reenergize the relay when the said signal is in an intermediate position and the said advance block is unoccupied.

10. In a directionally controlled block signal system, a stretch of single track divided

into block sections, a track relay for each block section, a plurality of signals along the track way, a line relay in control of each signal, normally closed overlapping line circuits controlling said line relays, a normally energized stick relay operative when deenergized to incapacitate the control by one line circuit of the line circuit in the rear, a circuit closer for the stick circuit of said relay controlled by the track relay of the said advance block and operative to be closed when the block is unoccupied, a second circuit closer for the stick circuit in multiple with the first circuit

closer and operated by the signal for said advance block to be closed when the signal is in either its clear or stop positions and to be open when the signal is in an intermediate position, and a restoring circuit for the said stick relay controlled by the line relay of said advance block and the circuit closer for said signal, said restoring circuit being arranged to be closed when the said signal is in an intermediate position and the line relay is energized.

In witness whereof, I hereunto subscribe my signature.

ROBERT J. HEWETT.
